UNITED STATES PATENT OFFICE.

EDWIN H. COLPITTS, OF EAST ORANGE, AND HAROLD DE FOREST ARNOLD, OF MAPLEWOOD, NEW JERSEY, ASSIGNEES, BY MESNE ASSIGNMENTS, TO WESTERN ELECTRIC COMPANY, INCORPORATED, A CORPORATION OF NEW YORK.

TRANSMISSION OF INTELLIGENCE.

1,388,450.

Specification of Letters Patent. Patented Aug. 23, 1921.

Application filed September 3, 1915, Serial No. 48,789. Renewed January 13, 1921. Serial No. 437,125.

To all whom it may concern:

Be it known that we, EDWIN H. COLPITTS and HAROLD DE FOREST ARNOLD, citizens of the United States, residing respectively at 5 East Orange, in the county of Essex and State of New Jersey, and Maplewood, in the county of Essex and State of New Jersey, have invented certain new and useful Improvements in the Transmission of Intelligence, of which the following is a full, clear, 10 concise, and exact description.

This invention relates to the transmission of intelligence, and more particularly to systems in which sustained oscillations of high 15 frequency are employed as carrier waves, and in which the amplitude of such oscillations is made to vary in accordance with variations in message waves of comparatively low frequency.

Its object is the production of high frequency waves which are accurately modulated in accordance with the message wave and of sufficient power for effective long distance communication.

To these ends the invention provides for the generation of carrier waves of the required high frequency, but of a power value comparable with that of the message impulses, as distinguished from that ultimately required for effective transmission. It further provides for modulating or changing the amplitude of these oscillations of low power in accordance with the form of the message wave and for amplifying the power 35 value of the modulated high frequency oscillations to a degree sufficient for long range communication.

The arrangement of this invention makes it possible to use, as the low frequency message source, a telephone transmitter or other device capable of handling only a small amount of energy, whereas in previous systems it has been assumed that for effective long range communication it was essential 45 that the low frequency-message source should be one capable of handling an amount of power comparable with that necessary for radiation.

In other words, the power value of the 50 generated oscillations is chosen with reference to the power delivered by the primary modulating source rather than with reference

to the amount of power necessary for radiation.

The invention will be more clearly understood by reference to the accompanying drawing, in which Figure 1 represents the system of this invention arranged for radiotelephonic transmission; and Fig. 2 shows an improvement on the system of Fig. 1, incorporating certain specific modifications which are the inventions of others and which have been made the subject matter of other patent applications.

Referring to Fig. 1, 3 is a thermionic amplifier of the well known type, having a filamentary cathode 4, an anode 5, and a grid or input electrode 6. The input circuit of this amplifier includes the cathode 4, the electrode 6, secondary winding 7 of transformer 8, 70 and battery 9 whose function it is to give the electrode 6 a negative potential with respect to cathode 4. The output circuit of the amplifier 3 includes the anode 5, condenser 10, primary winding 11 of transformer 12, winding 13 of transformer 14, condenser 15, battery 16 and the cathode 4. An impedance coil 17 is inserted, as shown, to provide a direct current path for space current supplied to the amplifier 3 by the battery 16. 80

Secondary winding 18 of transformer 14 is bridged across the cathode 4 and electrode 6, as shown, and serves to feed back, into the input circuit of the amplifier, currents generated in the output circuit, thereby causing 85 the amplifier 3 to function as a generator of high frequency oscillations, the periodicity of which is determined by the adjustment of condensers 10 and 15. For a more complete understanding of this action, reference may 90 be had to the Colpitts Patent 1,137,384.

Primary winding 19 of transformer 8 is connected through another transformer 20 to a source of low frequency impulses, which in this case comprises a telephone transmitter 21 and a battery 22. By this arrangement the telephonic electromotive forces, generated by transmitter 21 in the winding 7, serve to vary the amplitude of the high frequency oscillations produced by the amplifier 3, and cause 100 to be impressed on the transformer 12 a modulated high frequency wave whose envelop will have the form of the telephonic wave impressed.

The secondary 23 of transformer 12 combines with condenser 24 to form a resonant circuit which is tuned to the frequency of the high frequency carrier waves generated by 5 amplifier 3. Bridged across the terminals of condenser 24 is a resistance 25 of several thousand ohms. This resistance serves as a load of constant impedance on the transformer 12 and has the effect of steadyng the 10 action of the system. The resistance 25, in parallel with the condenser 24 and the winding 23, is included in the input circuit of an amplifier 26, also of the thermionic type.

Amplifier 26 serves in the well known manner to amplify the power value of the modulated high frequency oscillations produced by the amplifier 3. In this case, this power amplification is directed mainly to increasing the voltage of the modulated high frequency to the degree necessary for controlling the input circuits of the high current amplifiers 27, 28 and 29.

The features of design, whereby a thermionic amplifier of the type in question may 25 be made to produce either a voltage amplification or a current amplification, are discussed in the Arnold Patent No. 1,129,942 of March 2, 1915, and the Arnold Patent 1,329,283 of January 27, 1920.

30 The output circuit of amplifier 26 includes the inductance 30 for providing a direct current path for the space current delivered to the amplifier 26 by battery 31. In multiple with the inductance 30 is a condenser 32 which forms with it an anti-resonant circuit 35 tuned to the frequency of the high frequency oscillations, and consequently of high impedance thereto.

The input circuits of the current amplifiers 27, 28 and 29 are bridged in multiple 40 across the terminals of condenser 32. This and also other arrangements for producing the same result are disclosed in the Arnold Patents, 1,129,942 and 1,129,943 of March 45 2, 1915. In the present case, the cathodes 33, 34 and 35 are connected in series with a battery 36 and an adjustable resistance 37, and are heated to the required degree of incandescence by current supplied from this 50 battery.

The common output circuit of the amplifiers 27, 28 and 29 includes winding 38 of the output transformer 39 and a source of direct current, which, in this case, is shown 55 as a direct current generator 40, though it is obvious that any other source of direct current may be employed. A condenser 41 is preferably shunted about the terminals of the generator 40 in order to furnish a low 60 impedance path for the high-frequency currents.

The secondary winding 42 of the transformer 39 is connected in series with the antenna 43, and serves to impress thereon high-frequency currents of large power value 65

modulated in accordance with the telephonic wave generated by transmitter 21.

The amplifiers 27, 28 and 29 are preferably of the high current type described in the Arnold Patent No. 1,129,942 and in Arnold's application, Serial No. 277,578, filed February 17, 1919, and while, for the sake of illustration, only three of these amplifiers are herein shown, it has been found in practice that any number of such amplifiers 75 may be connected in multiple, depending upon the amount of power required, and that two or three hundred of such amplifiers connected in multiple produce a power amplification sufficient for effective long 80 range communication.

In the development of the system of Fig. 1, which is illustrated in Fig. 2, a slightly different method for modulating the high frequency oscillations is employed. In this 85 case, the high frequency oscillations are generated in a separate thermionic amplifier 50, whose operation will be found described in patent to Hartley 1,356,763, patented October 26, 1920, and which is designed to generate sustained oscillations of a frequency sufficiently high for radiation from an antenna but of a power value comparable with that developed by the transmitter 21. These high frequency oscillations, together with the oscillations of telephonic frequency, are impressed upon the input circuit of an amplifier 51 and serve to produce in the output circuit of this amplifier a modulated high frequency wave similar to that developed by the amplifier 3, as described and claimed in the patent to Van der Bijl 1,350,752, patented August 24, 1920. These modulated high frequency oscillations are subjected to a voltage amplification by 90 means of a plurality of amplifiers of the type of 26, whose filaments 52 are heated in multiple from a common direct current source 53.

The space current for both the amplifier 51 and the amplifiers 26 is supplied from a direct current generator 54, preferably shunted in each case by condensers 55 and 56 of about 1 microfarad capacity each. In this case the output circuit of the voltage 105 amplifiers 26 is coupled by the winding 57 to the resonant circuit made up of the winding 58 and condenser 59. Condenser 59 is shunted by a high resistance 60 and is included in the input circuit of the power amplifiers 27, 28, etc.

It has been found feasible to heat the filaments 33, 34, etc., from an alternating current source, and, as shown in Fig. 2, the filaments 33, 34, etc., are heated from a 110 cycle generator 61. Where an alternating current source is employed for this purpose, the filament circuit should be shunted by an inductance 62, the middle point 63 of which is connected to the output circuit through a 115 120 125 130

resistance 64. Each half of the inductance 62 is shunted by a condenser 65.

In a practical employment of the system herein described in which effective long range communication has been obtained, 5 six voltage amplifiers of the type of 26 were employed, and were supplied with space current from a generator 54 of 500 volts output. 250 of the amplifiers of the type 10 of 27 and 28 were employed, and were supplied with space current from a direct current generator 66 shunted by a condenser 67 of 100 microfarads capacity and delivering space current at a voltage of 600. The filament circuit was supplied by a 60 cycle generator 61 delivering current at a voltage of 10 volts. The inductance 62 was given a value of .4 milli-henry and the condensers 65 each had a capacity of 100 microfarads. 15

20 Although this invention has been described in connection with radio signaling, it is also applicable to selective transmission of any kind and to high frequency transmission over conducting circuits as 25 well as to radio transmission.

What is claimed is:

1. The method of signaling which consists in modulating carrier waves of insufficient power for transmission to a distant station and in increasing the power of said modulated waves before they are transmitted.

2. The method which consists in modulating, in accordance with other waves, 35 carrier waves of insufficient power for transmission to a distant station and in increasing the power of said modulated waves before they are transmitted.

3. The method which consists in modulating, in accordance with electric current waves, carrier waves of insufficient power for transmission to a distant station and in increasing the power of said modulated waves before they are transmitted.

45 4. The method which consists in modulating, in accordance with signal currents, carrier waves of insufficient power for transmission to a distant station and in increasing the power of said modulated waves before they are transmitted.

50 5. The method of signaling which consists in generating carrier waves, supplying message impulses of a power value comparable to that of said waves, modulating said waves in accordance with said impulses and in amplifying the power value of the modulated waves to a degree sufficient for long distance transmission.

60 6. In a signaling system, the combination of means for supplying modulated carrier waves, a conductor adapted to transmit said waves, and an amplifier between said means and said conductor whereby said waves are amplified before they are sent to 65 a distance.

7. In a signaling system, the combination of means for supplying modulated carrier waves, a conductor adapted to transmit said waves, and a vacuum tube of the audion type between said means and said conductor whereby said waves are amplified 70 before they are sent to a distance.

8. In a signaling system, the combination of means for supplying modulated carrier waves, a conductor adapted to transmit said waves, and a plurality of vacuum tubes of 75 different types connected in tandem between said means and said conductor.

9. The method of controlling the emission of high power, high frequency waves 80 by means of feeble signal waves which consists in generating feeble high frequency oscillations, modulating said oscillations in their feeble state by means of said feeble signals, and amplifying said feeble modulated oscillations to the high power state 85 in which they are to be transmitted.

10. The method of controlling the emission of high power, high frequency waves by 90 means of feeble signal waves which consists in generating feeble high frequency oscillations, modulating said oscillations in their feeble state by means of said feeble signals, and separately amplifying the voltage and amperage of said feeble modulated oscillations. 95

11. The method of controlling the emission of high power, high frequency waves by means of feeble signal waves which consists in generating feeble high frequency 100 oscillations, modulating said oscillations in their feeble state by means of said feeble signals, amplifying the voltage, and subsequently amplifying the amperage of the modulated oscillations. 105

12. The method of controlling the emission of high power, high frequency waves by means of feeble signal waves which consists in generating feeble high frequency 110 oscillations, modulating said oscillations in their feeble state by means of said feeble signals, amplifying said feeble modulated oscillations into modulated oscillations having a relatively high voltage, and in amplifying said high voltage modulated oscillations into modulated oscillations having both a relatively high voltage and a relatively high amperage. 115

13. The method of controlling the emission of high power, high frequency waves 120 by means of feeble signal waves which consists in generating feeble high-frequency oscillations, modulating said oscillations in their feeble state by means of said feeble signals, and causing said modulated oscillations to vary the potential across the input circuit of a system of thermionic amplifiers 125 having a large power output.

14. The method of radio transmission which comprises modulating a carrier wave 130

- 4
- 5 of insufficient power for transmission to a distant station, increasing the power of said modulated wave before transmission, and radiating the energy of said increased power wave.
15. The method of radio telephony which comprises modulating a carrier wave in accordance with speech waves, increasing the power of said modulated carrier wave before transmission, and radiating said wave of increased power.
16. A transmission system comprising means for supplying carrier waves of insufficient power for transmission to a distant station, means for modulating said waves, and means for increasing the power of said modulated waves before transmission.
20. A signal system comprising a source of carrier waves, means for modulating said waves in accordance with signals, a carrier wave transmission conductor, and means connecting said modulating means and said conductor for increasing the power of said modulated waves.
25. The method of transmitting signals through space which consists in generating oscillations of radio frequency having a power value comparable with that of the signal impulses to be transmitted, impressing said oscillations together with said impulses on the input circuit of a thermionic repeater, whereby modulated high frequency oscillations are produced in the output circuit of said repeater, and causing said modulated oscillations to vary the potential across the input circuit of a system of thermionic amplifiers having a large power output.
30. 19. In a signaling system, the combination of means for supplying carrier waves modulated in accordance with signal currents, a conductor adapted to transmit said waves, and an amplifier between said means and said conductor whereby said waves are amplified before they are sent to a distance.
35. 20. In a signaling system, the combination of means for supplying carrier waves modulated by other waves, a conductor adapted to transmit said waves, and an amplifier between said means and said conductor whereby said waves are amplified before they are sent to a distance.
40. 21. The combination with means for generating high frequency oscillations and for modulating said oscillations in accordance with low frequency impulses to be transmitted, of a plurality of current amplifiers arranged in multiple, and a voltage amplifier energized by said means and working into said current amplifiers, whereby the power of said modulated oscillations is increased.
45. 22. The combination with means for generating high frequency oscillations and for modulating said oscillations in accordance with low frequency impulses to be transmitted, of a plurality of thermionic amplifiers arranged in multiple having a common input circuit, and a thermionic amplifier adapted to be energized by said means and working into said input circuit, whereby the power of said modulated oscillations is increased.
50. 23. The combination with means for generating high frequency oscillations and for modulating said oscillations in accordance with low frequency impulses to be transmitted, of a plurality of thermionic current amplifiers arranged in multiple having a common input circuit and a common output circuit, a thermionic voltage-amplifier associated with said means and working into said input circuit, whereby the power of said modulated oscillations is increased and an antenna circuit coupled with said output circuit.
55. 24. The combination with a thermionic amplifier having an input circuit and an output circuit, of means for impressing a high frequency electromotive force on said input circuit, other means for impressing on said input circuit a low frequency electromotive force of an amplitude comparable with that of said high frequency electromotive force, whereby the amplitude of the oscillations produced in said output circuit is relatively small and is made to vary in accordance with the variations in said low frequency electromotive force, and means connected with said output circuit for amplifying said high frequency oscillations to the high power state in which they are to be transmitted.
60. 25. In a system for radio transmission, the combination with a thermionic amplifier having an input circuit and an output circuit, of means for impressing an audio frequency electromotive force and a radio frequency electromotive force of comparable and feeble intensities on said input circuit whereby a low power modulated high frequency current is produced in said output circuit, and means for amplifying said modulated current to a high power state in which it is to be transmitted.
65. 26. In a system for radio transmission, the combination with a thermionic repeater having an input circuit and an output circuit, of means for impressing an audio frequency electromotive force and a radio frequency electromotive force of comparable magnitudes on said input circuit whereby a modulated high frequency current is produced in said output circuit, and a plurality of thermionic repeaters coupled with said output circuit for amplifying said modulated high frequency currents to a high power value.

27. The method of carrier current telephony which includes generating speech waves and carrier current waves of comparable magnitude, impressing all of said waves upon a modulator, amplifying the modulated carrier waves and transmitting them to a distant station, said carrier waves before amplification being too feeble for transmission and reception at said station.
- 10 28. The method of high frequency transmission which includes generating low frequency modulating waves and carrier cur-

rent waves of comparable magnitude, impressing all of said waves upon a modulator, amplifying the modulated carrier waves 15 and transmitting them to a distant station, said carrier waves before amplification being too feeble for transmission and reception at said station.

In witness whereof, we hereunto subscribe 20 our names this 31st day of August, A. D. 1915.

EDWIN H. COLPITTS.

HAROLD DE FOREST ARNOLD.
